United States Patent Office

Des. 185,370
Patented June 2, 1959

185,370

CLOCK

Haig M. Kinosian, Whittier, Calif.

Application August 18, 1958, Serial No. 52,275

Term of patent 14 years

(Cl. D42—7)

Fig. 1 is a perspective view of a clock showing my new design.

Fig. 2 is a reduced rear elevational view thereof.

The dominant features of the design reside in the portions shown in full lines.

I claim:

The ornamental design for a clock, substantially as shown and described.
